UNITED STATES PATENT OFFICE.

MARCUS ADLER, OF CHICAGO, ILLINOIS.

TIME-CARD, PAY-ENVELOP, AND DAILY-PRODUCTION RECORD.

1,392,613.

Specification of Letters Patent.

Patented Oct. 4, 1921.

Application filed December 9, 1920. Serial No. 429,410.

To all whom it may concern:

Be it known that I, MARCUS ADLER, a citizen of the United States, residing at Chicago, in the county of Cook and State of Illinois, have invented certain new and useful Improvements in Time-Cards, Pay-Envelops, and Daily-Production Records, of which the following is a specification, reference being had therein to the accompanying drawing.

This invention relates to a combined time-card, daily production-record, and pay-envelop, and is adapted for use in factories where a large number of operatives are employed on a time and piece-work basis, and particularly in tailoring establishments.

An object of the invention is to provide a record, on a single paper-instrumentality, of the time and daily-production of a workman, and which instrumentality can be used as a pay-envelop, thereby obviating the necessity of writing out the record on a separate time-card and using an additional pay-envelop. My improvement therefore contemplates an improved type of envelop, suitable for receiving the operative's wages, and having certain data, made from time to time, upon which such wages are computed.

Another object of the invention is the arrangement of the data on the envelop in such a manner that, after filing the record, it can be readily located by the identifying data placed thereon.

In order that the invention may be more readily comprehended, I have disclosed the same in the accompanying drawings, these being, however, merely illustrative of a preferred and practical embodiment of the invention.

40 In these drawings:

Figure 1 is a view of one side or face of the record-envelop; and

Fig. 2 is a view of the reverse side thereof.

In these drawings, the numeral 1 designates an envelop, which may be of any size or shape that will lend itself to the accurate keeping of the desired or required record, and which may be made of a single sheet of paper. This envelop comprises a

50 face 2 and a back 3, each bearing suitable printed directions or legends for receiving certain data for the record, and gummed closure-flaps 4 and 4'. The edges of the sheet forming the envelop are brought together at A and sealed.

55

In order that an accurate record may be kept of the hours when a workman is on duty, the face 2 of the envelop bears certain printed matter or legends with suitable blanks for filling in necessary information. 60 For instance, the upper portion 5 is provided with a space for the insertion, at the extreme upper part thereof, of the workman's number and name and, immediately below this data, the amount earned. The 65 central portion 6 is also provided with a space for the insertion of the day of the week for which the record is kept, and the space immediately below this is ruled or divided into sections or columns for entering additional data. In the column designated by the numeral 8, spaces are provided for entering the day of the week, which is usually printed therein when the envelop is inserted in the time-clock, and which column bears the legend "Day"; in column 9, the time the employee reported for work and which bears the identifying legend "Morning in"; in column 10, the time the workman stopped work for lunch and which bears the identifying legend "Noon out"; in section 11, the time he resumed work after lunch, and which bears the identifying legend "Noon in"; in section 12, the time he finished work 75 for the day and which is indicated by the legend "Night out"; in columns 13 and 14, the overtime made on any day and the hour when the same was started and completed, and which columns bear the identifying legends "Extra in" and "Extra out"; and, 80 in column 15, the total number of working hours during the day. These several columns or sections are preferably in alignment with each other and, as here shown, are in horizontal alignment. They are also of sufficient width to receive the printing of the standard time clock. In order to keep an accurate record of the production of each workman, the record-clerk enters, on the reverse side of the envelop, in the space marked 18, the total number of units of production during each day. In this way, 85 a record of the efficiency of a workman is kept.

The lower portion 16 of the face provides 90 spaces for the entry of the total number of working hours during the week, and which is identified "Total time," the rate of pay, therefor, and which bears the legend "Rate," 95 and the total amount of wages earned for 100 105 110

that period, and which is identified by the legend "Total wages for week."

On the reverse side 3 of the envelop, means are provided for keeping a record of data 5 when the workman is engaged on piecework. To this end, a space is provided for the insertion of the workman's number and the character or class of work being done, and which space bears the identifying legends 10 "No." and "Class of work."

The back 3 is similarly ruled to form columns or sections for the necessary entries: For instance, the rate of pay on the particular class of work is entered in the column 15 designated 19 and which is identified by the expression "Rate," and any extras are noted in column 20, which bears the legend "Extras." For keeping an accurate record of the units of production of each workman 20 engaged on a piece-work basis, space 21 is provided for the insertion of the total number of articles completed, and which space is designated "Units," the rate in column 22 which is designated "Rate," any extras 25 in column 23 which is designated "Extras," and the total amount earned during the day in column 24 which is designated "Amount."

Each day, the envelops are collected and the amount earned is entered in the space 30 provided therefor, and the daily record is then charged to the pay-roll. At the end of the week or similar period, the amounts of each day—as noted on either or both sides of the envelop—are added up, and the total 35 is indicated on the face 2 of the envelop. Preferably, the flap of the envelop is turned in until the end of the week and just preceding the placing of the money therein, when it is withdrawn and sealed prior to delivery 40 to the workman.

When used as a time-card, the record-keeper fills out an envelop for each workman, entering the date of the month, the employee's name, and his clock number. 45 These envelops are then placed in a rack beside the time-clock, and each time the workman goes on and off duty, he stamps the time in the space provided therefor on the envelop, in the customary manner.

When the envelop is to be used as a record 50 for piecework, the blank spaces on the back 3 are filled out in the particulars as to date, number, and name, the same as when the envelop is used as a time-card, and the record 55 keeper enters, in the spaces provided, the class of work and the number or "units" of articles completed or charged to the workman, with the rate of pay therefor, the several sections or columns being in alinement 60 with each other.

After the record-keeper has computed the amount earned, either on the hour or piece-work basis, he enters the number of hours or the number of completed articles or 65 "units" in the space opposite the legend

"Total time," appearing on the face of the envelop; then, on the line below, he enters the rate of pay therefor; and, on the bottom line, he enters, opposite the expression "Total wages for week," the total amount of 70 wages due. This amount is also entered in the space provided therefor at the top 5 of the envelop. This sum is then placed in the envelop and the flap 4 sealed preparatory to distribution to the workman whose name 75 and number are indorsed at the top of the envelop.

When the records are in the custody of the time clerk, they are usually kept in a drawer in an upright position. If the clerk 80 finds it necessary to locate the record relating to any particular workman, this can be done by simply turning the tops of the envelops and selecting the one bearing the desired workman's number, the arrangement 85 of the data on the envelop being such that the location of the envelop can be accomplished quickly and without withdrawing the records of other workmen to ascertain the numbers printed thereon.

This system of record-keeping has been found particularly useful in establishments employing large numbers of female help where the State laws have fixed the maximum number of hours of labor for such 95 female help. It is possible to ascertain, very quickly, from my record whether the employee is a man or a woman, and the total number of hours of employment during any and every working day.

In systems for the keeping of records of the time or piecework of an employee with which I am familiar, three separate and distinct sets of records must be kept: In the first place, a time-card or piece work card 105 is made out and then, at the end of the week, the pay envelop must be made out. With my system, these records can simultaneously be kept on a single envelop, combining these two steps in the one record, thereby giving the workman a complete statement of the hours made each day, or the number of articles or "units" completed, the rate of pay, the total in hours or "units" for the week, 110 and the amount earned. Thus, a single instrumentality—in the form of a wage-receiving envelop—suberves a multifarious function, namely, to carry certain data and to contain the wages earned on those data.

From the foregoing, it will be apparent 115 that I have devised a record-system which, by the use of a single envelop, is adapted for the keeping of an accurate record of the hours of daily employment of a workman, with the rate of pay therefor, the total number of hours of employment during a given period of time, and the total amount of pay 120 thereof, in combination with means for keeping an accurate record of any employee engaged in piecework, including the num- 125 130

ber of completed articles or "units" turned in, the rate of pay therefor, and the total number of completed articles and the amount earned during a given period of time.

The combined time-card, daily production record, and pay-envelope forming the subject-matter of the present invention is well adapted for use in conjunction with any of the "coupon register systems" now in more or less general use in plants of different kinds; but it is to be understood that its use is not limited to that field. In fact, it is within the contemplation of my invention to employ the same in various and many different ways.

What I claim is:

1. A record-keeping system comprising an envelop having on one face a series of rulings which divide the same into a commercial form having appropriately designated spaces of size to receive entries of an employee's work hours, and having on its reverse face a series of rulings which divide the same into a commercial form having appropriately designated spaces of a size to receive entries of an employee's time-work data, there being on one of the faces a series of rulings to form appropriately designated spaces of size to receive entries of the total time, rate, and weekly wage-total noted in the aforementioned spaces on both faces

of the envelop; the envelop being open at one end to receive and hold the employee's earnings, as noted in said last-mentioned spaces.

2. A record-keeping system comprising an envelop having a series of rulings which divide the face thereof into a form having appropriately designated spaces of size to receive entries of an employee's work hours, including number of hours of work for a defined period, an employee-identifying legend including a number and a name space, and an amount-earned spaced; and having on its reverse face a series of rulings which divide the same into a form having appropriately designated spaces of size to receive entries of an employee's "No., " "Class of work," and "Piece-work" data; said "No." space being located adjacent one side of the envelop, said "Class of work" space being located in proximity thereto, and said "Piece-work" receiving space being located beneath said "No." and "Class of work" spaces; the envelop being open at one end to receive and hold the employee's earnings as noted in said "Amount earned" space.

In testimony whereof I affix my signature in presence of two witnesses.

MARCUS ADLER.
